WAVE GUIDE IMPEDANCE ELEMENT

Arthur Gardner Fox, Red Bank, N. J., assignor
to Bell Telephone Laboratories, Incorporated,
New York, N. Y., a corporation of New York

Original application July 30, 1942, Serial No.
452,851. Divided and this application August
17, 1945, Serial No. 610,956

19 Claims. (Cl. 178—44)

1

This invention relates to guided electromagnetic wave transmission and more particularly to impedance elements and terminations for wave guides.

An object of the invention is to provide simple series resonant impedance branches and simple parallel resonant impedance branches for use in wave guides.

Another object of the invention is to provide a reflectionless termination for a wave guide.

A uniform metallic sheath with or without a dielectric filler will serve as a guide for suitable electromagnetic waves. In cross-section the sheath may be circular, rectangular, or of other shape. For all frequencies above a minimum, known as the cut-off frequency, the guide acts like a transmission line and has a specific propagation constant and characteristic impedance. For any particular frequency there are an infinite number of cross-sectional sizes and shapes of guide which will have the same characteristic impedance.

Shunt reactive elements are obtained by placing partial obstructions across the wave guide. For dominant transverse electric waves a shunt reactive element may be provided by a transverse metal partition having a slit therein which extends substantially from one side to the other. If the slit is perpendicular to the direction of polarization of the electric field the element is primarily capacitive, and if parallel with the field the element is primarily inductive.

In accordance with the present invention an aperture in a transverse partition in a wave guide is proportioned to provide both inductive and capacitive components in the right amounts to resonate at a particular frequency. Depending upon the shape of the aperture the resonance thus produced may be either of the parallel type, offering a high shunt impedance across the guide, or of the series type, offering a low shunt impedance. For example, a rectangular aperture may be proportioned for parallel resonance or, if made sufficiently narrow, for series resonance. The resonance may be sharpened by providing inwardly extending projections on opposite sides of the opening. A wider opening may be used if the opposed edges of the aperture are made thicker, or if the two halves of the partition are made to overlap.

Also in accordance with the invention a reflectionless termination for a wave guide is provided by employing a parallel-resonant element followed by means within the guide for establishing a point of zero potential. The element is

2

preferably so designed that its effective shunt resistance is approximately equal to the characteristic impedance of the guide. The point of zero potential is spaced approximately a quarter wavelength from the element and may be established by means of a solid transverse metallic partition.

This is a division of United States application Serial No. 452,851, filed July 30, 1942, now Patent No. 2,432,093, issued December 9, 1947.

The nature of the invention will be more fully understood from the following detailed description and by reference to the accompanying drawings, in which like reference characters refer to like parts and in which:

Figs. 1 and 2 are perspective views of wave guides having therein partitions with apertures which provide reactive elements;

Fig. 3 shows a wave guide termination in accordance with the invention employing a parallel-resonant element;

Fig. 4 shows an impedance element in accordance with the invention that may be adjusted for either parallel or series resonance; and

Figs. 5 and 6 show series-resonant elements in accordance with the invention.

Taking up the figures in more detail, Fig. 1 is a perspective view of a section of a metallic wave guide 1 in the form of a rectangular sheath which has been cross-sectioned just ahead of the transverse metallic partition comprising an upper portion 2 and a lower portion 3 with an aperture 4 therebetween extending from one side of the guide to the other. If the guide 1 is carrying dominant transverse electric waves with the electric field 'E' polarized in a direction perpendicular to the length of the aperture 4, as indicated by the arrow, the partition will provide a shunt capacitive reactance. The magnitude of this reactance depends upon the width of the aperture 4 in the direction of the electric field 'E' and decreases as the width is decreased.

Fig. 2 is similar to Fig. 1 except that the aperture 4 extends from the top to the bottom of the guide 1 and has its length parallel to the direction of the electric field 'E'. A partition of this type provides a shunt inductive reactance, the magnitude of which also decreases as the width of the aperture 4 decreases.

By properly proportioning the aperture, a partition in a wave guide may be made to provide both inductive and capacitive components in the right amounts to resonate at a particular frequency. This may be either a parallel resonance or a series resonance. For example, Fig. 3 shows

a parallel-resonant element, that is, one providing a high shunt impedance, in a rectangular wave guide 1. The partition 11 has a symmetrically placed aperture 12 having a height V in a direction parallel to the electric field E and a width W perpendicular thereto. There are an infinite number of different apertures which will produce parallel resonance but once either the height V or the width W has been chosen, the other dimension is thereby determined. The line 13 gives the locus of the upper right-hand corner 14 of all possible rectangular apertures that will provide parallel resonance in the wave guide 1.

Associated with each height V of the aperture 12 in the parallel-resonant element shown in Fig. 3 there will be a resistance which is effectively shunted across the guide 1. The value of this resistance decreases as the dimension V decreases and its range may extend from a small fraction of the characteristic impedance of the guide 1 to infinity. It is possible, therefore, to design a particular resonant aperture which will have a shunt resistance equal to the characteristic impedance of the guide. Such an element placed in the guide and followed by a solid metallic partition such as 15 placed one-quarter of a wavelength behind the element 11 will serve as a reflectionless termination for the guide 1. A termination of this type uses no conventional resistance elements. The power is dissipated by high circulating currents in the metal partition 11 which has high thermal conductivity and is in metallic contact with the walls of the guide 1 and therefore is capable of dissipating a large amount of power. The element 11, when used in a termination of the type described, is preferably made of a metal having comparatively low electrical conductivity such, for example, as iron, since it is thereby possible to make the aperture larger.

Fig. 4 shows a circular guide 7 having therein an impedance element which may be adjusted for either parallel resonance or series resonance. The partition 16 has a rectangular aperture into which project a pair of threaded studs 17 having their axes along a diameter of the guide 7 and parallel to the electric field E. The two internally threaded sleeves 18, each with a circular metal plate 19 fastened to one end, may be screwed onto the studs 17. The separation between the plates 19 may thus be adjusted as desired. For series resonance only a small separation is required. For parallel resonance the spacing will be greater and in this case the plates 19 may not be required. An advantage of using an aperture with one or more inwardly extending projections, as shown in Fig. 4, is that sharper resonances may be obtained.

Fig. 5 shows an element more particularly adapted for series resonance, providing a low shunt impedance. The partition 16 has a symmetrical aperture 20 having its length perpendicular to the electric field E and its width constricted toward the center by means of the inwardly extending projections 21 and 22, to which are attached, on opposite sides of the partition 16, two overlapping metal flaps 23 and 24. These flaps 23 and 24 may be bent toward or away from each other to adjust the spacing therebetween and thereby the resonant frequency of the element.

Fig. 6 shows a modification of the series-resonant element of Fig. 5 in which the flaps 23 and 24 are replaced by two opposing metallic

plates 25 and 26 which are perpendicular to the partition 16 and attached to the ends of the projections 21 and 22.

Since a metallic obstruction in a wave guide usually produces a point of low potential and high current, it is preferable that the partitions be secured to the walls of the guide by soldering, welding or in some other appropriate manner such that a good electrical contact is obtained. It should also be noted that thinner partitions than those shown in the drawings, will, under some circumstances, produce more satisfactory results. The partitions have been shown thicker in the drawings only in the interest of clarity.

Certain subject matter disclosed herein is claimed in application Serial No. 266,179 filed January 12, 1952.

It is to be understood that the above-described arrangements are illustrative of the application of the principles of the invention. Numerous other arrangements may be devised by those skilled in the art without departing from the spirit and scope of the invention.

What is claimed is:

1. In combination, a conductively sheathed wave guide, means for establishing electromagnetic waves therein, a partition transversely disposed at a point in said guide, and a rectangular aperture in said partition, the height of said aperture in the direction of polarization of the electric field of said waves and the width of said aperture in a direction perpendicular thereto being proportioned with respect to each other to provide at said point a shunt impedance branch which is resonant at the frequency of said waves.

2. The combination in accordance with claim 1 in which said partition is comparatively thin.

3. The combination in accordance with claim 1 in which said aperture is symmetrically positioned in said partition.

4. The combination in accordance with claim 1 in which said guide is rectangular in cross-section.

5. In combination a conductively sheathed wave guide, means for establishing electromagnetic waves therein, a partition transversely disposed at a point in said guide and a rectangular aperture in said partition, the height of said aperture in the direction of polarization of the electric field of said waves and the width of said aperture in a direction perpendicular thereto being proportioned with respect to each other to provide at said point a shunt impedance branch which is parallel-resonant at the frequency of said waves.

6. In combination, a conductively sheathed wave guide, means for establishing electromagnetic waves therein, a partition transversely disposed at a point in said guide, and a rectangular aperture in said partition, the height of said aperture in the direction of polarization of the electric field of said waves and the width of said aperture in a direction perpendicular thereto being proportioned with respect to each other to provide at said point a shunt impedance branch which is parallel-resonant at the frequency of said waves and the resistance of said branch being approximately equal to the characteristic impedance of said guide.

7. The combination in accordance with claim 6 and means within said guide for establishing a point of zero potential, said means being spaced from said partition approximately a quarter of a wavelength at said frequency.

8. The combination in accordance with claim 7 in which said partition is made of a metal having comparatively low electrical conductivity.

9. The combination in accordance with claim 8 in which said metal is iron.

10. The combination in accordance with claim 5 and a solid metallic transverse partition within said guide spaced from said apertured partition approximately a quarter wavelength at said frequency, the effective shunt resistance associated with said apertured partition being approximately equal to the characteristic impedance of said guide.

11. In combination, a conductively sheathed wave guide, means for establishing therein electromagnetic waves, and an apertured partition transversely disposed in said guide, said partition being parallel-resonant at the frequency of said waves and the effective shunt resistance associated with said partition being approximately equal to the characteristic impedance of said guide.

12. The combination in accordance with claim 11 and means for establishing a point of zero potential within said guide approximately a quarter wavelength from said partition.

13. In combination, a metallic pipe-shaped guide having a rectangular cross-section for propagating electromagnetic waves dielectrically, exciting means for establishing within said guide electromagnetic waves, and a partition substantially perpendicular to the direction of propagation of said waves, said partition being provided with a rectangular shaped slot which is tuned to be resonant to the frequency of said waves.

14. In combination, a hollow-pipe type wave guide for transmitting electromagnetic waves dielectrically, exciting means for establishing electromagnetic waves in said guide, a metallic wall member associated with said guide and positioned transverse thereto relative to the direction of wave propagation through said guide and comprising an opening tuned to the frequency of the exciting means thereby effecting a concentration of the potential incident to the waves, and means for controlling the effective dimensions of said opening for controlling the frequency at which said opening is resonant.

15. In combination, a wave guide comprising essentially a pipe-like member, means connected to said member for establishing electromagnetic waves within said member, a wall member substantially perpendicular to the longitudinal axis of said first member and having therein an aperture which is tuned to the frequency of exciting electromagnetic waves to effect a concentration of one component of the electromagnetic field for producing a concentrated region of the field intensity, and means for controlling the effective dimensions of said aperture for controlling the frequency at which said aperture is resonant.

16. In combination, a dielectric wave guide of the hollow-pipe type, exciting means for establishing electromagnetic waves within said guide, a metallic wall positioned in said guide and lying in a plane substantially transverse to

the direction of wave propagation through said guide and provided with an aperture having an appreciable dimension perpendicular to the electric component of the field incident to the propagation of said waves through said guide and tuned to the frequency of said exciting means, and means for controlling the effective dimensions of said aperture and for controlling the frequency at which said aperture is resonant.

17. In combination, a dielectric wave guide of the hollow-pipe type, exciting means for establishing electromagnetic waves within said guide, a metallic wall positioned in said guide and lying in a plane substantially transverse to the direction of wave propagation through said guide and provided with an aperture having an appreciable dimension perpendicular to the electric component of the field incident to the propagation of said waves through said guide and tuned to the frequency of said exciting means, and mechanical means for controlling the effective dimensions of said aperture and for controlling the frequency at which said aperture is resonant.

18. In combination, a dielectric wave guide of the hollow-pipe type, exciting means for establishing electromagnetic waves within said guide, a metallic wall positioned in said guide and lying in a plane substantially transverse to the direction of wave propagation through said guide and provided with an aperture having an appreciable dimension perpendicular to the electric component of the field incident to the propagation of said waves through said guide and tuned to the frequency of said exciting means, and means for controlling the effective configuration of said aperture and for controlling the natural resonance frequency thereof.

19. In combination, a metallic pipe-shaped guide having a rectangular cross section for propagating electromagnetic waves dielectrically, exciting means for establishing within said pipe-like member electromagnetic waves, and a radiative wall substantially perpendicular to the direction of propagation of said waves and being provided with a rectangular shaped slot which is tuned to be resonant to the frequency of said exciting means.
